KEY FOR OPERATING A MAGNETIC LOCK

Wells F. Stackhouse, Ashville, N.Y., assignor to
American Locker Company, Inc., Jamestown, N.Y.

Filed Feb. 3, 1975, Ser. No. 546,507

Term of patent 14 years

Int. Cl. D8—07

U.S. Cl. D8—136

Fig. 3.

Fig. 1.

Fig. 4.

FIG. 1 is a front elevational view of a key for operating a magnetic lock showing my new design, the rear being the same as the front shown;

FIG. 2 is an elevational view taken from one side thereof, the opposite side being a mirror image of the side shown;

FIG. 3 is a top plan view thereof; and

FIG. 4 is a bottom plan view thereof.

I claim:

The ornamental design for a key for operating a magnetic lock, as shown and described.
